UNITED STATES PATENT OFFICE.

JABEZ B. FELLOWS, OF AUGUSTA, MAINE.

IMPROVEMENT IN CLOTHES-DRIERS.

Specification forming part of Letters Patent No. 121,349, dated November 28, 1871.

To all whom it may concern:

Be it known that I, JABEZ B. FELLOWS, of Augusta, in the county of Kennebec and State of Maine, have invented a new and valuable Improvement in Clothes-Driers; and I do hereby declare that the following is a full, clear, and exact description of the construction and operation of the same, reference being had to the annexed drawing making a part of this specification, and to the letters and figures of reference marked thereon.

Figure 1 of the drawing is a vertical central section view of my invention. Fig. 2 is a transverse central section through the collar.

This invention has relation to a clothes-drier having a vertical post and folding arms; and the novelty consists in the construction and arrangement of an adjustable sliding collar, designed for the purpose of keeping the arms extended, as hereinafter described.

In the accompanying drawing, A represents a vertical post, cylindrical in form, and supported in the ground or on a suitable sill provided for it. B designates a cap pivoted to the top of the post and provided with the lugs C, to which are hinged the diagonal brace-arms d. D designates a collar constructed with lugs d', to which are hinged the long arms E. To the arms E are pivoted, as shown, the arms d. The collar D is arranged to slide up and down the post A to ex-

pand or fold up the arms E. F designates ropes stretched from one to the other of the arms E, and used to hang clothes on. G indicates a collar encircling the post A below the collar D. It is constructed with a square lug, G', projecting from one side. This lug is recessed on its inner, upper, and lower sides, and holds a flanged plate, g, the inner surface of which is concave to coincide with the form of the post A. This plate is adjustable, and is actuated by means of a thumb-screw, h, passing through the lug G' from the outside. By means of said plate and screw the collar G may be fastened at any point along the post A to which it may be moved. The function of this collar is to support the arms E in an extended position, as shown.

What I claim as my invention, and desire to secure by Letters Patent, is—

The collar G, constructed with the lug G', and holding the plate g and adjusting-screw h, when applied to a clothes-drier having movable arms E, in the manner and for the purpose set forth.

In testimony that I claim the above I have hereunto subscribed my name in the presence of two witnesses.

JABEZ B. FELLOWS.
